UNITED STATES PATENT OFFICE

ALBERT E. PAGE, OF BROOKLYN, NEW YORK, ASSIGNOR TO SCOTT & WILLIAMS, INCORPORATED, OF NEW YORK, N. Y., A CORPORATION OF MASSACHUSETTS

CHAIN CONTROL FOR SPLICING ATTACHMENTS

Application filed July 25, 1929. Serial No. 380,909.

This invention relates to an attachment for circular knitting machines by which a spliced area of varying width may be formed in a knitted fabric.

The object of the invention is to make it practicable and of no difficulty to knit a fabric with spliced areas of constant width or of a width that is varied in either direction, i. e., widened or narrowed, through successive courses and in which the changes from an area of one sort to an area of another sort may be frequent and may be at any point in the length of the fabric.

A preferred embodiment of the invention is described hereinafter and is illustrated in the accompanying sheets of drawings to which, in the course of the description, reference is made.

In the drawings—

Figure 1 is a partial view in elevation of one side of a circular knitting machine to which the present invention has been applied.

Figure 2 is a partial view in elevation of the rear of the same machine.

Figure 3 is a view in elevation of the front of the same part of the machine shown in Figure 2.

Figure 4 is a partial, skeleton view from the front of a circular knitting machine having a modified form of chain control for the splicing attachment shown herein.

Figure 5 is a diagram of the foot of a stocking which may be made by use of the present invention.

Figure 6 is an end view of the cam drum showing the reversible drive mechanism for the movable cam segments.

Figure 7 is a view of the same cam drum, partly in section, taken from the left side of Figure 6.

Figure 8 is a development of the cam segments of the cam drum shown in Figures 6 and 7, the movable members being in their

outermost position forming practically a full circumference high portion.

Figure 9 is a similar view but with the movable members in their side by side position forming the maximum low portion.

In the drawings and description the invention is shown and described as it is applied to the well known Scott & Williams type of seamless hosiery machine with revolving needle cylinder but it should be understood that the invention is applicable to many other types of seamless hosiery machine.

The machine has the usual needle cylinder 260 revolvably mounted in the bedplate B and yarn fingers such as the splicing yarn finger F mounted above the needle cylinder on a pin 554 on the pivoted latch ring 550. This latch ring is pivoted on a bracket 401 on the bedplate B, as usual. The yarn fingers are adapted to be lifted out of and lowered into operative position by thrust rods 460 controlled by the usual cam lugs 501 on the main pattern drum 120 which is racked around at irregular intervals throughout the making of the stocking by any suitable mechanism, such for instance as is shown in the patent to Robert W. Scott Number 1,152,850 granted September 7, 1915. The needle cylinder is adapted to reciprocate or rotate, the reciprocating movement being obtained from a segment gear (not shown) by means of a train of gears including a constantly revolving gear 60. This construction is known and needs no further description.

The variable cam drum 10 turns with a horizontal shaft 12 which is mounted at the back of the knitting machine in spaced brackets 13 and 18. The shaft 12 is driven by the engagement of a small pinion 14 fixed on its end with the continuously revolving gear 60 which drives the segment gear or quadrant in the usual manner. The gear ratio is such that the cam drum 10 turns once for each revolution of the needle cylinder. This cam drum causes the raising and lowering of the

splicing yarn finger F by its action upon a link 15 which is attached at one end to the outer end of the yarn finger F and at its lower end to a reverse motion lever 17 pivoted at 16 on the shaft bracket 18 so that its free end may rest on the cam drum 10. The free end of the lever 17 is extended laterally as at 19 to give a wide bearing surface over the drum.

10 The yarn finger F being in its yarn feeding position, that is, resting on the throat plate 559, by reason of the main pattern drum's having been turned until there is no cam lug under the thrust rod 460, the extent 15 of each course through which the yarn finger is in that position is determined by the cam drum 10. Thus the main pattern drum which controls various operations of the machine in a predetermined time relation, determines 20 the period in which the yarn finger may be lowered to feeding position; while the rotary cam drum 10 determines the extent of a course through which the splicing yarn is fed to that course during such period.

25 The variable cam drum 10 is described and claimed in Patent No. 1,848,970, issued March 8, 1932 to Exilius E. Paquette, and is shown here in Figs. 1 and 6-9 inclusive.

30 The variable cam drum 10 is made up principally of a cylindrical body 20, two cam segments 21 and 22 on its periphery forming together a cam with relatively variable high and low portions and a mechanism for moving these segments simultaneously in opposite directions about the axis of the drum and for reversing their movements.

35 Each cam segment is formed of two members, an outer cam piece, e. g. 21^a, which extends about half way around the drum, and 40 an inner ring, e. g. 21^b, which surrounds the cylindrical body 20. The two inner rings 21^b and 22^b are spaced axially on the cylinder 20 and each is toothed on its inward face over about half of its circumference to form 45 a rack. The cam pieces 21^a and 22^a are wider than the rings and are so secured to the rings by screws 23 that their inward faces have but a very slight clearance. Retaining collars 24 are removably secured to the cylinder 50 by set screws and serve to hold the cam segments from axial movement on the drum.

55 The cam segments 21, 22 are moved simultaneously in opposite directions about the axis of the drum by a small pinion 26 on the outer end of a spindle 27 which is so mounted on a radial axis that it places the pinion between the two rings 21^b and 22^b and in engagement with the rack teeth of both. The lower end of the spindle 27 rests on a thin 60 hard metal piece 28 at the bottom of a small radial bore 29. A larger radial bore 30 intersects a bore 31 at right angles thereto extending from one end of the cylinder 20 parallel to the axis but eccentric to it. The intersection of the two provides a chamber for

a worm 32 and wheel 33. The wheel is secured to the radial spindle 27 while the worm is mounted to turn with a short shaft 34 extending through the bore 31 which is parallel to the drum axis. The spindle 27 70 is supported, above the wheel 33, by an insert 35 which rests in a counterbore 36 of larger diameter than the bore 30 in which the wheel turns. Washers 37 are placed on either side of the wheel between it and the insert 35 on the one side and the bottom of the bore 30 on the other side.

75 The worm shaft 34 extends beyond the end wall of the cylinder 20 to receive its driving parts. A collar 38 is held on the shaft by a set screw 39 and thus provides an abutment against which there rests a ratchet wheel 40. On the other or outer side of the ratchet is a leather disc 41 and beyond that a collar 42 and the end portion of a spring presser 43, all held in place by the head of a screw 44 that threads into an axial bore in the outer end of the worm shaft. The spring presser 43 is a piece of leaf spring fixed at one end on a post rigid with the drum and slotted at its other end to straddle the screw head 44 and to engage the collar 43. The ratchet, the leather disc and the collar are not secured to the shaft positively but normally they turn with it by reason of being pressed against the inner collar 38 which is fixed to the shaft. The worm shaft 34 is held from endwise movement by a small screw 45 which extends from the outside of the cylinder 20 to engage a groove 46 in the shaft.

90 The ratchet may be turned in either direction and for this purpose two pawls are provided, one for turning the ratchet in one direction and the other for turning it in the opposite direction. One pawl is formed 95 somewhat as a toggle having two parts hinged together as at 47 in Figures 1, 2, 6 and 7. One part 48 of this pawl is pivoted, at its end away from the joint, on a fixed pin 49 extending from the end of the cylinder 100 at a point remote from the axis thereof. The free end of the other part lies near the ratchet wheel being drawn inward against a fixed guide pin 50 by a spring 51 which is connected between the two parts of the pawl across the joint 47. A spring 52 held at one 110 end to the cylinder 20 and at the other to a projection of the pivoted part 48 beyond the pivot 49, tends to swing the pawl away from the ratchet wheel.

115 The other pawl similarly is made up of two parts, one of which is pivoted. This latter part is a lever pivoted at a central point on a pin 53 fixed to the end of the cylinder in such a way that one arm 54 of the lever extends out from the drum substantially radially while the other arm 55 lies toward the drum axis. These two arms are spaced axially so that the outward one 54 lies in a plane 120 spaced from the plane of the hinge 47 to the 125

other pawl. This inward arm is drawn toward a stop pin 56 by a spring 57 and carries a pivot pin 58 for the member 59 which engages the ratchet. This ratchet engaging member 59 is drawn by a spring 61 towards a 5 guide pin 62 extending endwise from the cylinder.

The cam mechanism just described provides a circular cam having members which 10 form a high portion consisting of the cam pieces 21^a and 22^a and a low portion consisting of that much of the exposed portions of the rings 21^b and 22^b which lie between the remote ends of the cam pieces. The ratio 15 between the high and low portions is varied by turning the pinion 26 and thereby causing the cam pieces to move in opposite directions. The low portion may be reduced to zero by moving the cam pieces until they are 20 on opposite sides of the cylinder and from a continuous circumferential high portion. When moved to position such that the two cam pieces lie side by side with their ends in register, the maximum low space is created. 25 If the cam pieces are exactly half of the circumference, this maximum low space is a half circumference. It is desirable however to make the cam pieces less than a half circumference in length, thereby enabling the 30 provision of a low space longer than a half circumference. When such is the case, a fixed cam piece is provided on the cylinder 20 in a position alongside of the cam segments where it can bridge the space between the ends of the 35 cam pieces when they are moved from their side by side positions to their extreme positions as shown in the patent to Paquette, No. 1,848,970, previously referred to. In this manner a continuous full-circumference high 40 cam portion may be obtained in one setting and a low portion longer than a half circumference may be had by another setting.

To restrain the cam pieces from movement beyond the point at which they give the 45 desired maximum high portion when they are moved thereto from their side by side position, and beyond the side by side position on their return thereto under reverse movement, stops are provided. These consists of pieces 50 of thin metal secured by screws to the drum, the screws extending through elongated holes in the stop pieces so that the stops may be adjusted circumferentially on the drum. One stop 65 is secured to the retaining ring 24 adjacent the cam segment 21 and has an offset portion 66 lying over the ring 21^b in the path 55 of the cam piece 21^a and in such a position that it engages the trailing end of the latter when 60 the cam segments are moved outwardly from their side by side position. The position determined by this stop gives the maximum high portion and, if the stop is properly set for the purpose, it gives a full circumference high 65 portion which causes the yarn finger to be

held out of feeding position throughout the course.

The other stop 67 is secured to the cylinder 20 in the space between the cam rings 21^b and 22^b. It has an upturned portion 68 in the path of a pin 69 carried on the side face of the ring 21^b. The stop is set so that the pin strikes it when the cam pieces are in their side by side position then providing the maximum low space. This position is the one illustrated 70 in Figure 9. When further movement of the cam segments is prevented by the stops, the driving mechanism therefor may continue to operate but it is rendered ineffective by the slip clutch which comes into play under such 75 conditions.

The manner in which the cam segments are moved outward from and back to their side by side positions by the ratchet and its actuating pawls will be understood by considering the 80 effect of a succession of movements of the pivoted member 48 of one pawl and then of the pivoted member 54, 55 of the other pawl. As the member 48 is moved inwardly about its pivot 49 by a striker mechanism to be described, the pawl, guided by the pin 50, engages the ratchet and turns it. The spring 52 returns the pawl to its normal position. The turning of the ratchet normally causes 85 the worm shaft to turn because the friction connection between the ratchet and the inner collar 38 under pressure of the spring 43 and the screw 44 maintains the driving relation. Thus through the worm 32 and wheel 33 the pinion 26 is turned. Depending, of course, upon the direction of the thread on the worm 32, this turning causes either outward or backward movement of the cam segments but it will be assumed here that the turning of the 90 pinion caused by the pawl member 48 is such that it moves the cam segment outward from their side by side position in which the maximum low space is created toward the position forming a full-circumference high cam. The 95 opposite engagement of the pinion with the rack teeth on the two cam rings 21^b and 22^b is the cause of course, of the opposite movement of the cam segments.

Movement of the other pawl, caused by 100 rocking the arm 54 in a way which is yet to be described, causes the ratchet 40 to turn in the opposite direction since the pawl member 59 moves against the ratchet teeth in the opposite direction from that of the other pawl. The result is a reverse movement of the cam 105 segments or a movement toward their side by side or registering position.

The stops 65 and 67 limit the permissive 110 movements of the cam segments and prevent further relative movement between them when they have established a predetermined ratio between the high and low portions regardless of whether or not the ratchet continues to be turned in a given direction after 115 the stop has been reached. This is possible 120

because of the friction connection between the ratchet 40, the driven member and the driving member, the worm shaft 34 affording a capability of slip. When movement of the cam segments is resisted, the ratchet slips on the collar 38 and turns ineffectively.

A mechanism now to be described, operated from the main pattern chain 85, controls the cam mechanism described above by selecting the pawl to be actuated and by determining the duration of the operative and the inoperative period of each pawl and the relation of these periods to the other operations of the machine in knitting the stocking. The selection of the pawl to be operative determines the direction of drive of the reversible mechanism described above for effecting relative movement between the members which form the high and low portions of the rotary cam.

It will be recalled from the preceding description that the hinge 47 and pivoted member 48 of one pawl turn in a plane parallel to but spaced from the plane in which the pivoted arm 54 turns, both being secured to the end of the cam drum 10. This permits selective actuation of them by moving a striker into their respective planes in position to engage them as they turn. This striker is a small lug 71 mounted fixedly on a horizontal rod 72 below and inside of the drum shaft 12. The striker rod is supported in the bracket 18 at one end and at the other end in a bushing 73 on the main frame of the machine and it is movable horizontally in these supports. A spring 74 tends to move the rod to the right in Figure 2. The horizontal movement enables the striker 71 to be put in any desired one of its three selective positions, viz. (1) clear of the pawls, (2) in the path of the hinge 47 and the pawl member 48, (3) in the path of the pivoted pawl member 54.

The selection of the position which the striker 71 shall assume and the mechanism for moving it to such position are under control of the main pattern chain 85 which is moved at regular intervals in correspondence with the knitting of predetermined numbers of courses. The mechanism for moving the chain in this manner may be of any suitable sort, e. g. that shown in the Scott Patent No. 1,152,850 referred to above.

A system of levers is interposed between one end of the movable striker rod 72 and the chain, its part at the chain taking the form of a short finger 86 (Fig. 3) in the path of lugs on the chain. This finger is part of a lever 87 which is mounted on the cross rod 93 upon which the clutch slide 92 is supported as described in the Scott Patent 1,152,850. The finger 86 either rests against the chain to permit the rod 72 to assume its position putting the striker clear of the pawls on the cam drum, (see Fig. 2), or it is moved by a low lug on the chain to push the rod 72 over so that the striker is in the path of the pawl

lever 54, 55 or, for a third position in which the striker is put in the path of the pawl 47, 48, the finger 86 is moved by a high lug on the chain 85.

According to the preferred way of controlling from the chain, the rocking lever 87 which is directly actuated by the chain lugs is the same member that controls a tucking attachment of a well known sort, exemplified by the form shown in the Page Patent 1,367,425. This tucking attachment is a mechanism for varying the position of a clearing cam whereby to cause the needles to form tuck stitches when the pattern so dictates. Since this tucking is not commonly done at the same part of the stocking as that in which splicing of the sort with which this invention is particularly concerned is done, it is possible to use the same rocking lever to control both the tucking and the splicing attachments from the chain.

The tucking attachment comprises the rod 121, which moves the clearing cam, (not shown here but shown in the Page patent mentioned above), and which has pivoted at its lower end a latch 123 held by the spring 123' normally in engagement with the upper side of an arm 124 that is integral with the rocking lever 87. The reciprocating lever 125 actuated in the usual way by the quadrant (as described in the Page Patent 1,367,425) strikes a wire 126 depending from a stud 127 on the latch so that when a lug on the pattern chain lifts the rocking lever 87 the latch 123 can remain in engagement with the arm 124 of the then lifted lever 87 only until tripped by the reciprocating lever 125. In this way the clearing cam is in action to cause tucking for a shorter time than that during which the pattern chain holds the lever 87 in lifted position.

To prevent the lever 87 from lifting the rod 121, and hence from moving the clearing cam at a time when it is desired to control the splicing from the chain by way of the lever 87, there is here provided a cam and an associated lever for moving the latch 123 beyond the end of the arm 124 so that as the latter lifts, it will not engage the latch. Such a cam may be associated with any part of the machine which acts in a cycle corresponding to the cycle of knitting for one article. Thus the main pattern drum 120 may be used but it is convenient to use the pinion 122 that is mounted on the shaft 80 upon which the sprocket wheel for the pattern chain turns. This gear drives the main pattern drum 120 through a gear train of a well known arrangement (described in the Scott Patent, 1,152,850) and turns once for each complete knitting cycle during which a stocking is formed. The mechanism for driving the gear 122 likewise is described in the aforementioned Scott patent.

On the side face of the pinion 122 is mount-

ed an arcuate cam 128. A wire 129 is adjustably secured to the stud 127 on the latch 123 and has its lower end in the path of the said cam. The arrangement is such that the 5 cam rides under the wire 128 after the completion of that portion of the stocking in which tuck stitches are desired. The result is that the latch is then swung outwardly and is held clear of the arm 124. Thereafter, the 10 lever 87 may be rocked by subsequently acting links on the chain for the purpose of controlling the splicing and without affecting the clearing cam. Various other arrangements are possible to secure this independence 15 of the splicing and the tucking in spite of their being controlled through the same medium. No undesirable interference occurs when the tucking attachment is in operation for even if the movement of the lever 87 for 20 this purpose does cause a shifting of the striker rod 72, it is of no consequence. The slip clutch and the stops on the auxiliary drum 10 prevent over-running of the segments and, in any event, the splicing yarn 25 fingers are held out of operation during that period by the lugs 501 on the main pattern drum.

The levers for transferring the movements of the rod 87 to the rod 72 may be of any suitable arrangement. When the arm 87 is rocked by a lug on the chain, it swings the arm 94 outwardly, this arm being an extension of the arm 124 that moves the lever 121 for the clearing cam. The arm 94 in turn 30 swings the freely mounted spindle 96 by means of a lever 95 fixed thereon and thus causes a swinging of the lever 97 which turns with the spindle and, being in engagement with the end of the rod 72, moves it to put the 35 striker in its operative position.

An alternative form is shown in Fig. 4. The lugs are put on one side of the chain and act directly upon a rod 98 which is slideable in brackets 99 fixed on the frame A and 40 on the machine frame, and is urged toward the chain by a spring 101. If desired, a bracing guide may be put on the opposite side of the chain to keep it in line with the rod 98 and to prevent its being moved by said 45 rod. The movement of the rod 98 is transferred to the striker shaft 72 by a lever 102 which turns on a pivot 103 on the frame A and which has a curved end 104 in engagement with the end of the striker shaft 72.

50 By the above described control from the pattern chain, frequent changes may be made in the shape of the spliced area as illustrated in Fig. 5. The splicing may take place in any part of the article being knit 55 since the movements of the pattern chain take place at regular intervals throughout the knitting of the article. A high lug on the chain causes the low portion of the rotary cam to be decreased, hence it causes a narrowing of the spliced area through suc-

sive courses. A low lug creates the opposite condition—the low portion of the cam is increased and the spliced area is widened. When there is no lug engaging the finger 86 (or the rod 98, Fig. 4) the ratio between the 70 high and low portions is unchanged and the width of the spliced area is constant through successive courses. The relative positions of lugs on the chain therefore determines the variation of the width of the spliced area. 75

As shown in Fig. 5, a stepped high splice S may be made in which the steps are of gradually increasing size. The sides of the steps may be diagonal or not as desired. It is possible also to narrow the spliced part S' of 80 the sole and thus effect a saving of yarn since it is not necessary that the spliced area in the sole be as wide through the instep as it commonly is made in seamless hose. If desired the edges of the spliced sole may be 85 scalloped by gradually narrowing and widening the splice successively. As will be apparent, the shape of the spliced area may be varied extensively due to many possible combinations of converging and diverging areas 90 and straight sided areas, and due to the fact that the changes from one shape to another 95 may be frequent.

It will be understood that during reciprocatory knitting when the heel pocket is being formed, the splicing yarn finger F is held out of feeding position by the action of the lug 501 of the main pattern drum 120 on the thrust rod 460. This is done in the usual manner. The striker 71 may be put in its neutral position during this period and thereafter may be put in the path of the pawl 47, 48 by a high lug just as the cam lug 501 moves away from under the thrust rod 460 to permit the splicing yarn finger to feed again. This enables the production of the gradually narrowing spliced area in the sole toward the instep. 100

If the stop 67 is set so that the pin 69 on the movable cam segment 21a engages it during the knitting of the last course in the high splice above the heel, it is not necessary to put the striker in neutral position during the knitting of the heel. Once a stop is reached the drive mechanism of the cam becomes ineffective due to the slip clutch 38. This may be availed of to prevent change of the setting of the cam while the heel is being made and then when the heel is completed the drive mechanism may be reversed by a change to a high lug on the chain. The low lug causes a decrease in the high portion of the cam so that the gradually narrowing spliced area may be knit in the sole. 110

The stop and the friction clutch are particularly useful in connection with a supplementary control, now to be described, which makes it certain that when the area to be spliced is reached, in the course of knitting an article, the rotary cam 10 will have 115 120 125 130

the correct ratio between its high and low portions to begin the splice with the width desired. The common practice is to begin the splice with a taper, hence the cam drum should be so set that a full circumference high portion is formed just prior to the beginning of the splicing. The splice usually ends with a portion of full width which makes it necessary to reverse the drive mechanism of the cam and to restore the full circumference high portion before the next spliced area is to be knit.

It also sometimes happens that, after a spliced area is partly made, some defect will be created which makes it necessary to discard the partly formed article and to begin a new one. If the machine were reset to put it in condition for beginning a new article without re-setting the rotary cam drum the latter would start the splice in the new article at the width at which the old one was being spliced when removed. The supplementary control prevents such a happening and makes it unnecessary to reset the cam drum manually. It also takes care of the resetting of the cam drum in the interim between the splicing of one full article and another when the last part of the splice in the article is of different width from that of the first part.

The mechanism for this purpose consists of a lug 106 on the main pattern drum and an associated set of levers for putting the striker in the path of the pawl 47, 48 to move the cam members to their fully extended position forming a full circumference high portion. This lug is so positioned that it moves the striker to this position far enough in advance of the knitting of the spliced area to insure the formation of the full circumference high portion well before the chain control comes into operation to effect the splicing. The stop 63 halts the cam segments in the desired position for initiating the splicing and this position is held until the splicing yarn finger is dropped to feeding position in the known manner, whereupon the chain lugs come into control. The same result may be effected by arranging high cams in succession on a part of the chain which passes the finger 86 (or the rod 98) ahead of the lugs which control the cam drum during the splicing period.

The levers operated by the lug 106 on the pattern drum to move the striker rod consist of a rocker 107 which carries the finger 108, directly engaged by the lug 106, and a reverse motion lever set which translates the movement of the rocker 107 into movement of the striker rod. This reverse motion set comprises a bell crank lever 109 pivoted on the bracket 18 so that one arm of it rests in a slot 111 in the end of the striker rod 72 while its other arm extends horizontally and is pivoted to the link 110 which is secured to one end of the rocker 107.

The mechanism herein described for association with an adjustable rotary cam gives a flexible control enabling the production of spliced areas in any part of the article and with frequent changes of width. It is capable of variation in detail within the fair scope of the following claims.

I claim—

1. In a circular knitting machine having needles, yarn fingers including a splicing yarn finger, a pattern drum determining the active period of said splicing finger and a pattern chain moved in correspondence with the knitting of the courses, said chain controlling the movement of said drum, a rotary cam having high and low portions for determining the extent of a course through which splicing yarn is fed thereto, said cam being adjustable to vary the effective ratio between said high and low portions, and means controlled by said pattern chain for adjusting said cam.

2. In a circular knitting machine having needles, yarn fingers including a splicing yarn finger, a pattern drum determining the active period of said splicing finger and a pattern chain moved in correspondence with the knitting of the courses, said chain controlling the movement of said drum, a rotary cam having members forming high and low portions determining the extent of a course through which splicing yarn is fed thereto, a mechanism for effecting relative movement between said members to vary the ratio between said high and low portions and means controlled by said pattern chain for determining the operative and inoperative periods of said mechanism.

3. In a circular knitting machine having needles, yarn fingers including a splicing yarn finger, a pattern drum determining the active period of said splicing finger, and a pattern chain moved in correspondence with the knitting of the courses and controlling the racking of said pattern drum, a rotary cam having members forming high and low portions for determining the extent of a course through which splicing yarn is fed thereto, a reversible drive mechanism for effecting relative movement between said members to increase and to decrease the ratio between said portions, and means controlled by said pattern chain for determining the direction of drive of said mechanism and its operative and inoperative periods.

4. In a circular knitting machine having needles, yarn fingers including a splicing yarn finger, a pattern drum determining the active period of said splicing finger, and a pattern chain moved in correspondence with the knitting of the courses and controlling the racking of said pattern drum, a rotary cam having high and low portions for determining the extent of a course through which

splicing yarn is fed thereto, said cam being adjustable to vary the ratio between said high and low portions, and means controlled by said pattern chain for adjusting said cam to vary the width of the spliced area, together with supplementary means to establish a predetermined ratio between said portions before said chain controlled means comes into operation to control the splicing.

5. In a circular knitting machine having needles, yarn fingers including a splicing yarn finger, and a pattern chain moved in correspondence with the knitting of the courses, a rotary cam having high and low portions for determining the extent of a course through which splicing yarn is fed thereto, said cam being adjustable to vary the ratio between said high and low portions, and means controlled by said pattern chain for adjusting said cam to vary the width of the spliced area, together with a pattern drum and means controlled thereby for establishing a predetermined ratio between said portions before said chain controlled means comes into operation to control the splicing.

6. In a circular knitting machine having needles, yarn fingers including a splicing yarn finger, a pattern drum determining the effective period of said splicing finger and a pattern chain moved in correspondence with the knitting of the courses, and controlling the racking of said pattern drum, a rotary cam having members forming high and low portions for determining the extent of a course through which splicing yarn is fed thereto, a reversible drive mechanism for effecting relative movement between said members to increase and to decrease the ratio between said portions, and means controlled by said pattern chain for determining the direction of drive of said mechanism.

7. In a circular knitting machine having needles, yarn fingers including a splicing yarn finger, a pattern drum determining the effective period of said splicing finger and a pattern chain moved in correspondence with the knitting of the courses, and controlling the racking of said pattern drum, a rotary cam having high and low portions for determining the extent of a course through which splicing yarn is fed thereto, said cam being adjustable to vary the ratio between said high and low portions and having means to limit the adjustability at points establishing predetermined ratios between said portions, and means controlled by said pattern chain for adjusting said cam, together with supplementary means co-operating with said limit means to establish a predetermined ratio between said portions before said chain controlled means comes into operation to control the splicing.

8. In a circular knitting machine having needles, yarn fingers including a splicing yarn finger, and a pattern chain moved in

correspondence with the knitting of the courses, a rotary cam having high and low portions for determining the extent of a course through which splicing yarn is fed thereto, said cam being adjustable to vary the ratio between said high and low portions and having means to limit the adjustability at points establishing predetermined ratios between said portions, and means controlled by said pattern chain for adjusting said cam, together with a pattern drum and means controlled thereby for establishing a predetermined ratio between said portions before said chain controlled means comes into operation to control the splicing.

9. In a circular knitting machine having needles, yarn fingers including a splicing yarn finger, and a pattern chain moved in correspondence with the knitting of the courses, a rotary cam having members forming high and low portions for determining the extent of a course through which splicing yarn is fed thereto, a mechanism for effecting relative movement between said members to vary the ratio between said high and low portions, stops for limiting the permissive relative movement between said members, means for rendering said mechanism ineffective for varying said ratio when said stops function, and means controlled by said pattern chain for determining the operative and inoperative periods of said mechanism, together with supplementary means to establish a predetermined ratio between said portions before said chain controlled means comes into operation to control the splicing.

10. In a circular knitting machine having needles, yarn fingers including a splicing yarn finger, and a pattern chain moved in correspondence with the knitting of the courses, a rotary cam having members forming high and low portions for determining the extent of a course through which splicing yarn is fed thereto, a mechanism for effecting relative movement between said members to vary the ratio between said high and low portions, stops for limiting the permissive relative movement between said members, means for rendering said mechanism ineffective for varying said ratio when said stops function, and means controlled by said pattern chain for determining the operative and inoperative periods of said mechanism, together with a pattern drum and means controlled thereby for establishing a predetermined ratio between said portions before said chain controlled means come into operation to control the splicing.

11. In a circular knitting machine having needles, yarn fingers including a splicing yarn finger, a pattern chain moved in correspondence with the knitting of the courses, a clearing cam and mechanism including a member acted on by said chain for moving said cam from a plain knitting posi-

tion to tuck producing position with respect to the needles, the combination of a mechanism controlled from the chain by said member for varying the extent of a course through which splicing yarn is fed and means for freeing said clearing cam mechanism from control by the chain at a predetermined point in the knitting cycle to permit the chain to control the splicing.

10 In testimony whereof I have signed my name to this specification.
